HYDRAULIC PRESS HAVING DIFFERENTIAL
AREA PREFILL VALVE RESPONSIVE TO
PULLBACK LINE RESTRICTIONRobert K. Sedgwick, Oak Park, Ill., assignor to
American Steel Foundries, Chicago, Ill., a cor-
poration of New Jersey

Application March 25, 1948, Serial No. 17,001

15 Claims. (Cl. 60—52)

1

This invention relates to hydraulic presses and more particularly to a novel actuating circuit for a pipeless hydraulic press of the type disclosed in my co-pending application, Serial No. 545,058, filed in the United States Patent Office on July 15, 1944, now abandoned.

A general object of the invention is to provide a novel circuit for a press, such as above described, wherein means are provided for initiating the relatively slow pressing speed of the device before the ram encounters resistance of the work. The circuit disclosed in the above-mentioned application is of the controlled gravity drop type in which the ram is allowed to drop at a rate dictated by the pump capacity until the work is contacted whereupon the work resistance automatically effects the change to pressing speed at which the full tonnage is available. Such a circuit while suitable for a large range of work is not suitable for operations requiring the change to pressing speed before contact of the ram or ram mounted tool with the work. A principal reason for this requirement is the well-known phenomena of rapid tool wear occurring under certain conditions when the tool enters the work at the rapid advance speed. In such applications tool life has been increased many fold by slowing the press just before contact between the work and the tool.

The primary object of the invention, therefore, is to design a pipeless circuit having the characteristics of great simplicity and compactness, being of economical construction, and capable of effecting the change from rapid advance to pressing speed prior to slowing of the ram in response to resistance of the work.

A more specific object of the invention is to provide a novel circuit wherein the change from rapid advance speed to pressing speed is effected by valve means responsive to restriction of the flow of hydraulic fluid from the pullback chamber of the press as the ram moves on its advance stroke.

Another object of the invention is to devise a circuit wherein the prefill valve means which connect the advance chamber of the press and the associated hydraulic reservoir are maintained in open position by pressure in the pullback line of the circuit, the prefill valve means being closed by restricting flow of fluid from the pullback chamber to the prefill valve means.

Still another object of the invention is to afford, in combination with the above-mentioned features, prefill valve means which close immediately upon restriction of fluid flow from the

2

pullback chamber and other valve means responsive to pressure in the main chamber for connecting the pullback chamber to the hydraulic reservoir until the operating pressure within the main chamber has been drawn off through the fluid supply system thereby preventing noise and shock to the reservoir resulting from opening of the prefill valve means while high pressures exist in the main chamber.

10 The foregoing and other objects and advantages of the invention will become apparent from a consideration of the following specification and the accompanying drawings, wherein:

Figure 1 is a side view of the hydraulic press embodying the invention, portions of the press being shown in elevation and other portions being shown in vertical section;

Figure 2 is a sectional view on the line 2—2 of Figure 1; and

15 Figure 3 is a view comparable to Figure 1 but illustrating a modification of the invention.

Describing the invention in detail and referring first to the embodiment shown in Figures 1 and 2, the press comprises a main cylinder casting, 25 generally designated 2, containing a ram 4 with a head 6 defining an advance chamber 8 and a return or pullback chamber 10 within the cylinder casting 2. The ram 4 is provided with a central bore or passage 12 connected to the pullback chamber 10 as by radial ports 14 and containing a pullback tube 16 slidably fitted in a restricted portion 18 of the passage 12 in fluid-tight engagement with said portion at the upper end of the passage.

30 The cylinder casting 2 supports a tank or reservoir 20 adapted to contain a suitable supply of hydraulic fluid such as, for example, oil. The cylinder also supports a bracket 22 carrying a conventional pump 24 preferably of the well-known variable discharge, reversible delivery type.

The bracket is connected in any suitable manner, as by cap screws (not shown), to the cylinder casting and is provided with advance and return ports 26 and 28 respectively, connected with advance and return lines 30 and 32 extending through the cylinder casting, the line 30 being connected to the main or advance chamber 8 and the line 32 being connected to the pullback tube 16. The bracket 22 supports a motor 34 operably connected to the pump 24 and a housing 36 for the motor.

45 It will be understood that in operation of the device, as hereinafter discussed in detail, the pump 24 alternately delivers pressure fluid to and exhausts pressure fluid from the respective lines

38 and 32 in such manner that the line 38 delivers pressure fluid when the line 32 is exhausted and vice versa. If desired, this may be accomplished by means of suitable valving rather than a reversible delivery pump such as that disclosed in the present case. However, an object of the present invention is to eliminate such valving and the necessary piping therefor.

The cylinder casting 2 also supports a prefill valve body 38 containing a cylindrical prefill valve chamber 48 having a smaller diameter portion 42 adapted to communicate through a passage 44 with a port or passage 46 connected to the advance chamber 8. A hollow prefill valve stem 48 reciprocates within the chamber 48 and comprises a smaller diameter portion 58 adapted to close the port 46 in the closed position of the stem. The stem portion 58 comprises ports 52 connected to the passage 44 and other ports 54 connected to the larger diameter portion of the chamber 48 beneath the larger diameter portion of the stem 48 which defines an annular chamber 56 connected to a passage 58 which is in turn connected by a passage 60 to the upper end of the pullback tube 16.

The prefill valve stem 48 comprises a cylindrical chamber 62 having a smaller diameter portion 64 receiving a smaller diameter portion 66 of a hollow valve stem 67 having a larger diameter portion 68 fitted into the larger diameter portion of the bore 62. The valve stem 67 is spring-pressed by a spring 70 to its closed position whereat the ports 52 are closed from communication with the ports 54 and the annular chamber 56. Sleeved over the portion 58 of the prefill valve stem 48 is an annular valve plate 72 adapted to close ports 74 connecting the chamber 56 with the passage 44.

It may be noted that each stem 48 and 67 is formed with a larger diameter portion and a smaller diameter portion whereby, as hereinafter described in connection with the operation of the press, the development of pressing tonnage in the advance chamber 8 acting against the relatively great pressure area of the stem 48 thrusts the same downwardly to closed position and also thrusts the valve stem 67 downwardly to open position against the resistance of spring 70.

The top of valve chamber 48 is connected to a conventional relief valve 76 adapted to discharge into the reservoir 20 to maintain a predetermined maximum pressure value within the advance chamber 8, and the passage 60 is connected by a passage 78 to a similar relief valve 80 adapted to prevent excessive pressure in the pullback chamber and associated conduits in the pullback phase of the operating cycle.

The body 38 supports an air chamber or cylinder 82 containing an air piston 84 and adapted for connection by a nozzle 86 to a conventional shop air line 88 preferably containing valve means 87 responsive to position of the ram for delivering compressed air at a value, for example, of about eighty pounds per square inch to the chamber 82 at the end of the desired rapid advance stroke of the ram 4. The piston 84 is connected to a stem or plunger 88 having a fluted lower end 90 which reciprocates within the pullback tube 16 in snug engagement therewith for a purpose hereinafter described in connection with the operation of the press.

In operation of the press, with the prefill valve stem 48 in open position due to pressure in chamber 56 caused by the weight of the ram 4, the operator initiates the rapid advance phase of the

cycle by actuating the pump 24 to the advance position thereof whereat fluid is drawn to the suction side of the pump from the pullback passage 32 and is delivered from the discharge side of the pump to the advance passage 38. Under these conditions the ram descends toward the work, forcing fluid from the pullback chamber 10 through the pullback tube 16 into the passage 32 and into the annular passage 56 holding the prefill valve stem 48 in the open position, inasmuch as the suction rate of the pump is less than the rate at which fluid is forced into the passage 56 and chamber 56 by the weight of the advancing ram 4. Thus, the stem 48 is held in open position accommodating flow of fluid from the hydraulic reservoir 20 to the advance chamber 8, since the pressure in chamber 56 is much greater than the atmospheric pressure of the fluid in reservoir 20 acting on the top and bottom areas of the valve stem 48, and in this connection it may be noted that the discharge of the pump 24 into the chamber 8 on rapid advance phase of the cycle is open to the reservoir 20 through passages 44 and 46 so that pressure in the advance chamber is substantially the same as the atmospheric pressure of the fluid in the reservoir 20.

At a predetermined point in the advance stroke of the ram, air pressure is admitted to the cylinder 82, either by manually operated or automatically operated valve means 87 responsive to position of the ram, to urge the piston 84 and plunger 88 downwardly cutting off or restricting the supply of fluid from the pullback tube 16 to the pullback passage 32. This causes a rapid drop in the pressure within the annular chamber 56 causing the prefill valve stem 48 to be sucked to the closed position shown in Figure 1 and sucking the annular valve plate 72 to its open position to accommodate supply of hydraulic fluid to the pullback passage 32 which is, under these conditions, delivering fluid to the suction side of the pump. With the valve stem 48 closed, pressure rapidly builds up in the advance chamber 8 acting on the larger diameter portion of the stem 48 to maintain it in tightly closed position and acting on the larger diameter portion 68 of the valve stem 67 to force the latter downwardly to the open position shown in Figure 1 whereat fluid is supplied from the reservoir 20 through the passage 44, the ports 52 and 54 to the annular chamber 56 which is in communication with the pullback line 32 thus insuring an adequate supply of fluid for the pump 24 while the latter is on the advance stroke thereof.

The great pressure of the ram 4 against the fluid in the pullback chamber 10 forces the plunger 88 and piston 84 upwardly to accommodate further escape of fluid from the pullback chamber 10 as the ram moves on its pressing stroke under full tonnage.

The pullback phase of the cycle is initiated by reversing the pump 24 and exhausting the cylinder 82 to maintain the plunger 88 in its open position. Under these conditions the pump directs pressure fluid to the pullback passage 32 and draws fluid from the advance passage 38. The fluid in the pullback passage 32 is exhausted through the passages 60 and 58 and the annular chamber 56 into the ports 54 and thence through ports 52 into the reservoir 20 inasmuch as the stem 67 is still in its open position accommodating flow of fluid through ports 52 and 54. When pressure within the advance chamber 8 is relieved sufficiently to accommodate closing of the stem 67, the pressure of the fluid trapped with-

in the annular chamber 56 urges the stem 48 to its open position whereat fluid from the advance chamber 8 is expelled through the passage 44 in the reservoir 20 as the ram moves on its pullback stroke preparatory to initiation of another cycle.

Figure 3 shows a modified valve mechanism in a press otherwise identical with that shown in Figures 1 and 2. Parts of the press in Figure 3 corresponding to those of Figures 1 and 2 are identified by corresponding numerals.

In the embodiment of Figure 3, the valve body 38 comprises a cylindrical chamber 41 receiving a cylindrical pistonlike portion 43 of a valve stem 48 which is connected to a valve member 47. All of these parts are sleeved over the plunger 88 and are adapted to perform the function of the corresponding valve means 67 and 72 of the previously described embodiment. Referring again to Figure 3, the body 38 is provided with a port 91 adapted to be closed against communication with the pullback line 32 and opened to communication therewith by means of the valve member 47, which is held in open position on the full pressure stroke by pressure fluid admitted to chamber 41 by means of a port 92 communicating with the top of the prefill valve chamber 40.

Thus on the rapid advance phase of the cycle, the ram 4 moves downwardly as fluid is pumped into the advance line 30 and is sucked from the pullback line 32. Under these conditions, the prefill valve stem 48 is held in its open position by pressure conveyed through the passage 58 to the annular chamber 56. This pressure is maintained by the fluid forced from the pullback tube 16 as the ram moves downwardly and this pressure is also effective to hold the valve member 47 in its upper or closed position.

The pressing or full pressure advance stroke of the ram 4 is initiated, as in the previously described embodiment, by actuation of the fluted plunger 88 to cut off the supply of fluid to the pump from the pullback tube 16 whereupon pressure in the passage 60 of the body 38 drops, accommodating movement of the prefill valve stem 48 to its closed position and at the same time sucking the valve member 47 to its open position whereupon the reservoir 20 is opened to communication through the port 91 and the passage 60 with the pullback line 32. As pressure builds up in the advance chamber 8, it is transmitted upwardly through the hollow prefill valve stem 48 which is provided with a central passage, indicated at 94. Under these conditions the pressure in the top of the prefill valve chamber 40 is effective to hold the valve stem 48 in its closed position inasmuch as the top pressure area thereof is substantially greater than the bottom pressure area. The pressure in the top of the chamber 40 is conveyed through the port 92 to the chamber 41 thereby acting against the top of the valve member 43 holding the valve member 47 in its open position to insure steady flow of fluid through the port 91.

The pullback phase of the cycle is initiated by exhausting the cylinder 82 to maintain the plunger 88 in its open position assumed, as in the previously described embodiment, under the great pressure developed on the full pressure stroke of the ram 4. At the same time the fluid supply is reversed so that the pressure fluid is admitted to the pullback line 32 and the advance line 30 is exhausted, the valve member 47 being maintained in its open position by the pressure

against the valve member 43 accommodating flow of fluid from the pullback line 32 and the port 92 into the reservoir 20 until the pressure within the chamber 8 has been bled off sufficiently to accommodate raising of the prefill valve stem 48 by the pressure in the passage 58 and to accommodate closing of the valve stem 47 whereupon the ram 4 moves on its pullback stroke urging fluid from the advance chamber 8 through the port 46 and passage 44 into the reservoir 20.

It will be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. In a system for actuation of an hydraulic motor having advance and return chambers, and ram means reciprocal therein; the combination of fluid supply means adapted in the advance position thereof to direct pressure fluid to the advance chamber and exhaust fluid from the return chamber and adapted in the return position thereof to deliver pressure fluid to the return chamber and exhaust fluid from the advance chamber, a reservoir of low pressure fluid, prefill valve means connecting said reservoir to said advance chamber, said valve means comprising a casing having a passage connecting said reservoir to said advance chamber, a valve stem slidably fitted in said chamber and having a passage extending longitudinally therethrough, the pressure area at the end of said stem remote from said advance chamber being greater than that adjacent said advance chamber whereby fluid pressure within the latter tends to hold said stem in the closed position thereof, said casing having a passage connected to the return chamber and to a portion of the casing containing an area of said stem opposed to the first-mentioned area thereof whereby fluid pressure delivered to the last-mentioned passage from the return chamber is effective under certain conditions to hold said stem in the open position thereof, valve means having opposed pressure areas acted upon by the fluid in the respective chambers, said last-mentioned valve means being adapted to open accommodating flow of fluid between the return chamber and the reservoir whenever the pressure in the advance chamber exceeds that within the return chamber by a predetermined value and adapted at other times to restrict flow of fluid between the reservoir and the return chamber, and means for restricting flow of fluid from the return chamber to the second-mentioned area and to the second-mentioned valve means during the advance position of the fluid supply means thereby terminating the rapid advance stroke of said ram means and initiating the full pressure advance stroke thereof.

2. In a system of the class described for actuation of an hydraulic motor having a cylinder carrying a pullback tube, and a ram having a head slidably fitted in said cylinder to define advance and return chambers therein, the ram being hollow and having the tube slidably fitted therein, and passage means connecting the interior of the ram with the return chamber; the combination of fluid supply means for delivering pressure fluid to the advance chamber while ex-

hausting the tube and for delivering pressure fluid to the tube while exhausting the advance chamber, a reservoir of low pressure fluid, prefill valve means comprising a casing with a passage connecting the advance chamber to the reservoir, a valve chamber in the casing, and a prefill valve stem in the valve chamber adapted to open and close the passage with respect to said advance chamber, said stem having a passage extending from end to end thereof and having a greater pressure area adapted to close the stem than that adapted to open the stem, a passage in said casing connecting the tube to a portion of said valve chamber containing an area of said stem adapted to open the same, valve means adapted to connect said last-mentioned passage to the reservoir when the pressure in the advance chamber exceeds that within the return chamber by a predetermined value and adapted at other times to cut off communication between the reservoir and the last-mentioned passage, and control means for cutting off communication between the tube and the last-mentioned passage when said pressure delivering means is on the advance stroke thereof.

3. A system, according to claim 2, wherein the control means comprises a plunger adapted to reciprocate within the tube, a piston and cylinder device operatively connected to the plunger, and a source of pneumatic fluid connected to said device.

4. A system, according to claim 2, wherein relief valve means are connected to the reservoir and to the prefill valve chamber and to the second-mentioned valve passage for maintaining the pressure in the advance and return chambers at predetermined values.

5. In an hydraulic circuit for actuation of an hydraulic device comprising advance and pullback chambers, and ram means reciprocal therein; the combination of means for alternately delivering fluid to and exhausting fluid from the advance and return chambers, a reservoir of low pressure fluid connected to the advance chamber, valve means having opposed pressure areas acted upon by the fluid in the advance and return chambers respectively, and adapted when the pressure in the advance chamber exceeds that in the pullback chamber by a predetermined value to accommodate flow of fluid between said reservoir and the pullback chamber and adapted at other times to restrict flow of fluid between said reservoir and the pullback chamber, prefill valve means in the connection between said reservoir and said advance chamber comprising a relatively great closing pressure area and a relatively small opening pressure area acted upon by the fluid in said advance chamber in the closed position of the prefill valve, said prefill valve having another opening pressure area connected to the pullback chamber, and means for cutting off communication between the last-mentioned area and the pullback chamber to terminate the rapid advance stroke of the device thereby enabling pressure fluid in the advance chamber to close the prefill valve means and to open the first-mentioned valve means to initiate the full pressure advance stroke of the device.

6. In a system for actuation of an hydraulic motor having advance and return chambers, and ram means reciprocal therein; the combination of means for alternately directing pressure fluid to and exhausting pressure fluid from the advance and return chambers, a reservoir of low pressure fluid having a connection to the ad-

vance chamber, prefill valve means for opening and closing said connection, said valve means comprising a hollow stem having a greater pressure area acted upon by pressure in the advance chamber tending to close the stem than the area tending to open the stem, said stem having another pressure area spaced from the first and second-mentioned areas and acted upon by the pressure in the return chamber during the rapid advance stroke and the return stroke of said ram means to hold said stem open, valve means adapted to automatically accommodate unrestricted flow of fluid between the return chamber and the reservoir when the pressure in the advance chamber exceeds that in the return chamber by a predetermined value, said valve means being adapted at other times to automatically restrict flow of fluid between the reservoir and the return chamber whereby the pressure in the latter chamber acts upon the second-mentioned area to hold said stem open, and yielding means for restricting flow of fluid from the return chamber to terminate the rapid advance stroke of said ram means and initiate the full pressure advance stroke thereof.

7. A system for actuation of an hydraulic motor having a cylinder, a pullback tube carried thereby, a ram having a head reciprocal in the cylinder and defining advance and return chambers therein, said tube being afforded a substantially fluid-tight fit within a passage in said ram, and passage means connecting said passage at all times to the return chamber; the combination of a reversible delivery pump having opposite sides thereof connected to the advance chamber and the tube respectively, a reservoir of low pressure fluid, prefill valve means adapted to open and close communication between the advance chamber and the reservoir, a passage connecting the tube to the prefill valve means for delivering pressure fluid thereto to open the latter on the return and the rapid advance strokes of the ram, a plunger adapted to restrict flow of fluid from the tube to the prefill valve means, compressible actuating means for the plunger, and valve means having opposed areas acted upon respectively by the pressure in the advance chamber and the tube, the last-mentioned valve means being adapted to open communication between the reservoir and the tube when the pressure in the advance chamber exceeds that within the tube by a predetermined value and adapted at other times to close communication between the tube and the reservoir.

8. A system, according to claim 7, wherein the second-mentioned valve means comprises a unit sleeved over the plunger and having a pressure area connected to the advance chamber and another pressure area connected to the tube.

9. A system, according to claim 7, wherein the prefill valve means comprises a stem with a passage extending longitudinally therethrough, the stem having a greater closing area acted upon by the pressure in the advance chamber than the opening area of said stem acted upon by the fluid in the advance chamber, the stem having another opening area connected to the tube, and the other valve means comprises a valve member slidably fitted within the stem passage and having opposed opening and closing areas connected to the advance chamber, the opening area being greater than the closing area.

10. In a system of the class described for actuation of an hydraulic device comprising advance and return chambers, and ram means reciprocal

therein; the combination of a reservoir of low pressure fluid, prefill valve means connecting said reservoir to the advance chamber and adapted to be maintained in a closed position by the pressure therein, said prefill valve means having an opening pressure area acted upon by the pressure in the return chamber, advance and return lines connected respectively to the advance and return chambers for alternately delivering pressure fluid to and exhausting pressure fluid from the advance and return chambers, and yielding means for restricting flow of fluid from the return chamber to the return line thereby diminishing the pressure against said area to accommodate closing of said prefill valve means and resultant initiation of the full pressure advance stroke of said ram means.

11. In a system of the class described for actuation of an hydraulic motor having advance and return chambers, and ram means reciprocal therein; the combination of a reservoir of low pressure fluid, a prefill valve means adapted to connect the reservoir to the advance chamber on the rapid advance stroke of the ram means and on the return stroke thereof and adapted on the full pressure stroke of said ram means to cut off communication between the reservoir and the advance chamber, said valve means comprising a pressure area acted upon by fluid pressure in the return chamber for maintaining the valve means in the open position thereof, and means for restricting flow of fluid from the return chamber to said area on the rapid advance stroke of said ram means to initiate the full pressure stroke thereof, the restricting means being adapted to yield under the pressure of fluid forced from the return chamber when the prefill valve means are closed and high pressure fluid is admitted to the advance chamber.

12. In a system of the class described for actuation of an hydraulic device comprising advance and return chambers, and ram means reciprocal therein; the combination of advance and return lines connected respectively to the advance and return chambers, means for alternately delivering high pressure fluid to one line and exhausting the other line, a reservoir of low pressure hydraulic fluid, prefill valve means for alternately opening and closing said reservoir with respect to said advance chamber, means for restricting flow of fluid from the return chamber to the return line on the advance stroke of said ram means, and means responsive to said restriction of flow for automatically closing said prefill valve means.

13. In an hydraulic circuit for an hydraulic device comprising advance and pullback chambers, and ram means reciprocal therein; the combination of a reservoir of low pressure fluid connected to the advance chamber, prefill valve means for opening and closing the connection between the advance chamber and said reservoir, and means responsive to restriction of flow from

the pullback chamber on the advance stroke of said ram means for closing said prefill valve means.

14. In a hydraulic circuit for a hydraulic device comprising advance and return chambers, and ram means reciprocal therein; the combination of a reservoir of low pressure fluid connected to the advance chamber, prefill valve means for opening and closing the connection between the advance chamber and said reservoir, means responsive to restriction of fluid flow from the return chamber on the advance stroke of said ram means for closing said prefill valve means, and means for restricting flow of fluid from the return chamber.

15. In a system for actuation of an hydraulic motor having a cylinder, and a ram reciprocal therein dividing the cylinder into advance and pullback chambers; the combination of a pullback tube slidably fitted within the ram and connected to the pullback chamber, a reservoir of low pressure fluid, prefill valve means for opening and closing communication between the reservoir and the advance chamber, said prefill valve means having a relatively great closing area and a relatively small closing area, both communicating with the advance chamber, and having another opening area communicating with the tube, means for alternately delivering high pressure to and exhausting fluid from the advance chamber and the tube, normally closed valve means adapted to open when the pressure in the advance chamber exceeds that in the tube by a predetermined value, said last-mentioned valve means being adapted when open to connect the pullback tube to the reservoir, and means for closing said prefill valve means comprising a plunger reciprocal to a position relative to the tube whereat flow of fluid therefrom is restricted to reduce pressure against said other opening area to a value whereat pressure on said relatively great closing area is effective to close said prefill valve means, and means for urging the plunger to said position after said ram has advanced any predetermined distance on its advance stroke, said last-mentioned means comprising means compressible by the pressure fluid in said tube when said prefill valve means are closed and pressure fluid is delivered to the advance chamber by said delivering means.
